UNITED STATES PATENT OFFICE

CLAUDE W. WATSON, OF PORT ARTHUR, TEXAS, ASSIGNOR TO THE TEXAS COMPANY, OF NEW YORK, N. Y., A CORPORATION OF DELAWARE

PROCESS FOR CONVERTING HYDROCARBONS

Application filed June 26, 1928. Serial No. 288,410.

The present invention relates to cracking processes wherein reflux condensate formed in the course of fractionation of the developed vapors is returned to the cracking zone for retreatment, and contemplates the removal from the reflux condensate certain of its lower boiling components before it is returned to the cracking zone.

The invention has in view particularly dephlegmating or fractionating vapors from a cracking still to form an overhead vaporous product, which is condensed to form a gasoline or other light distillate, and a plurality of reflux condensates, the heavier condensates being returned to the same cracking zone for retreatment.

In a preferred embodiment of the invention the evolved vapors from a cracking still may be subjected to fractionation to form a final vapor fraction which is condensed to yield gasoline or other light distillate desired, a heavy reflux condensate substantially free from light components which is returned to the cracking zone, and a light intermediate component or reflux condensate which is removed from the system.

My process, therefore, has particular reference to that part of cracking systems commonly known as fractionators, separators, dephlegmators or bubble towers which will hereinafter be called fractionators. It is into these parts of the apparatus that the vaporous products of the cracking reaction are led, and wherein they are separated or fractionated, the lighter from the heavier components.

In the practice of my process I preferably employ two fractionators, although it is to be understood that more than two fractionators may be employed if desired, for the present invention contemplates removing certain components from the system whose presence tends to retard or interfere with the conversion process. The vaporous products from the cracking zone entering the first fractionator are partially condensed therein and precipitating to the bottom of said first fractionator are subject to withdrawal therefrom, preferably for recycling through the system, while the lighter uncondensed com-

ponents pass off overhead in vaporous form preferably to the second fractionator for further fractionation therein. The heavier components of the vaporous products conducted overhead from the first fractionator are condensed in the second fractionator and precipitating to the bottom thereof are subjected to withdrawal preferably for discharge from the system while the lighter components in vaporous form pass off overhead to suitable condensing means and then to storage.

I have in mind producing refined hydrocarbons on a commercial scale and in the present invention contemplate the practice of an important improvement in the previously known methods of converting the higher boiling hydrocarbons into lower boiling ones.

Generally speaking the art of cracking is now well known to the petroleum industry. It is also known that, according to the method of treatment, a varying amount of decomposition and rearrangement of the hydrocarbon molecules of the oil under treatment may take place, when converting higher boiling hydrocarbons into lower boiling ones. This is especially noticeable when practicing a process or method wherein certain components of the products of conversion, formed during the period of decomposition and rearrangement are recirculated or recycled through the system for treatment.

For example if a crude petroleum from the well be fractionally distilled at substantially atmospheric pressure the components evolved may be gas, gasoline, kerosene, gas oil, lubricating stock and fuel oil stock. The crude or virgin gas oil thus derived may have an initial boiling point of say 450° F. and may form an excellent charging stock for cracking stills wherein it may be subjected to cracking conditions including a pressure of say 300 pounds per square inch and a temperature of about 825° F.

As the gas oil undergoes cracking it may be subjected to continuous withdrawal from the cracking zone while other gas oil may be conducted to the cracking zone at the rate the treated oil is withdrawn. Thus the oil undergoing treatment is being renewed con-

tinuously and at a constant rate whereby the time of treatment or conversion is fixed.

With the decomposition or breaking down of the relatively high boiling oil thus undergoing treatment there is set up a rearrangement of the atoms and a completely different product or products are formed. This newly formed product, from the standpoint of physical characteristics, may be said to resemble in a general way crude petroleum in that it may be fractionally distilled much as the crude oil previously mentioned. The fractional products of the said newly formed products may be classified as gas, gasoline, a product of rather wide distillation range resembling gas oil and a heavy residue suitable for fuel oil stock.

In the continuous conversion of a relatively high boiling gas oil charging stock into lower boiling products a certain fraction is formed which, as has been explained, may resemble the virgin gas oil charging stock. It has also been explained that the said fraction has a rather wide distillation range. Previous to my invention this entire fraction of evolved gas oil, in a cracking operation, has ordinarily been withdrawn in condensed form from a fractionator in the system and has been recycled through the cracking zone for retreatment.

When this fraction or evolved gas oil is processed under similar converting conditions but separately and in comparison with the original virgin gas oil from which the fraction was evolved, it has been found that the yield of gasoline from the evolved gas oil is relatively less than the yield of gasoline from the virgin gas oil.

However when the evolved gas oil is itself separated into two fractions and the two fractions thereof, the lighter and the heavier, are similarly processed, that is using the same pressures and temperatures, in comparison with each other and in comparison with said virgin gas oil, it has been found that the heavier fraction shows much better gasoline yields than the lighter fraction and better gasoline yields than the total evolved gas oil comprising both of said fractions, though a still slightly poorer gasoline yield than the original virgin gas oil charge.

It has thus been found in many cases that a considerable percentage of the virgin charge is converted into a lighter gas oil fraction that is relatively difficult to crack, and the recycling of said lighter fraction together with the heavier fraction amounts to the continuous recycling of a product which at best may be only slightly affected by the cracking conditions employed which are selected as most effective to the bulk of the product undergoing treatment. While I do not attempt to explain what causes this difference it is well recognized that lighter components such as light gas oil and kerosene having rela-

tively low critical temperatures are extremely difficult to crack.

Experiments in processing have established that the heavier fraction of the evolved gas oil responds relatively well to the cracking conditions best suited for the conversion of the virgin gas oil into lower boiling products; therefore the evolved heavy gas oil forms a good recycle stock from a standpoint of yields, while on the other hand the evolved light gas oil or fraction of the converted product responds slowly to the converting conditions which may be found to be most productive in the conversion of the virgin gas oil. In other words it is necessary to recycle the evolved heated gas oil through the cracking zone a number of times to accomplish any appreciable amount of conversion due to its content of lighter fractions. This is expensive and unprofitable, therefore it would be better to remove the evolved light gas oil from the system continuously as evolved.

In the regular operation of apparatus wherein higher boiling hydrocarbons are being converted into lower boiling ones, the evolved product, which I have previously described as a newly formed product, it being a product of cracking and resembling in a vague way a crude petroleum, is subjected to the first step in the separation or fractionation of its components in the cracking zone, wherein the residual unvaporized fraction settles to the bottom of the stills and is regularly withdrawn therefrom.

An overhead vapor which may have a temperature of approximately 790° F. and comprising the remaining components of the product of cracking; namely, the gas, gasoline and evolved gas oil, are delivered into a fractionator wherein these components are subjected to further separation or fractionation, the evolved gas oil being condensed and precipitated to the bottom of the fractionator while the gas and a gasoline distillate of approximately 400° F. end point are taken off overhead in vapor form.

As has already been pointed out, prior to my invention it has been the regular practice to remove all of the intermediate fractions namely those boiling above the gasoline range from the fractionating zone in condensed form, this condensate being the total evolved gas oil component formed, and to recycle said fractions through the system with the fresh charge of virgin gas oil.

According to the present invention, as previously stated, I preferably employ two fractionators and among other objects effecting in the first fractionator a close fractionation of the vaporous products of conversion issuing from the cracking or reaction zone, whereby only the heaviest fraction or the evolved heavy gas oil component of the vaporous product will be condensed and col-

lected in the bottom of the first fractionator. An overhead vapor composed of the evolved light gas oil, the gasoline and the gas components, will then be passed to a second fractionator for further separation by condensing therein the evolved light gas oil and withdrawing overhead in vapor form the evolved gasoline and gas components.

For example, I have previously disclosed, that a fresh stock or gas oil having an initial boiling point of say 450° F. may be converted. Then in the practice of my invention it would be preferable to condense in the first fractionating zone all fractions of the vaporous products of conversion from the cracking zone having an initial boiling point of approximately 450° F. and make them available therein for recycling for further conversion. It would accordingly be preferable to remove overhead in vaporous form all of the evolved lighter fractions or components having an end point of approximately 450° F. Where superatmospheric pressure is employed in the conversion it might be found advantageous to somewhat reduce the pressure within the first fractionator. The lighter components having an end point of approximately 450° F., leaving the first fractionator in vaporous form would preferably be delivered into a second fractionator. All of the gas and gasoline components, namely those having an end point of approximately 400° F., may preferably be removed overhead from the second fractionator in vaporous form and passed through condensing means enroute to storage, while the heavier components, namely the lighter gas oil or kerosene constituents having an initial boiling point of approximately 400° F. and an end point of approximately 450° F., may preferably be condensed and deposited in the bottom of said second fractionator subject to removal from the system. Within the second fractionator it may be found desirable to maintain a still further reduced pressure from that maintained in the first fractionator.

These objects of my invention as well as others may be better understood from the following description and the accompanying drawing which illustrates in diagrammatic elevation the preferred embodiment of an apparatus adapted for carrying out my process as described herein, although it will be understood that any form of suitable apparatus may be employed for practicing the process.

Referring to the drawing:

Fresh oil to undergo treatment is forced into the system preferably under several atmospheres of pressure and entering through the pipe 1 may pass through the closed coil 2 in heat exchange with the warm vaporous products in the top of fractionator 97 whereby the fresh oil is slightly preheated. It is then conducted through the heat insulated pipe 3 and is passed through the closed coil

4 in heat exchange with the warmer vaporous products in the top of the fractionator 90 whereby the said preheated oil is further heated.

The preheated oil passing through the heat insulated pipe 5 then enters the preheater coil 10, and is highly heated in transit therethrough.

Upon emerging from the preheater coil 10 the highly heated oil may be returned immediately to the heating zone for still further heating entering the heating coil 16 through a bypass pipe 11, the valve 12 therein being open and the valves 13 and 14 being closed. Preferably, however, the valve 12 is closed and valves 13 and 14 are open so that the oil leaving the coil 10 is conducted through the heat insulated pipe 15 and passed through the closed coil 20 in contact with a body of oil maintained in the bottom of the fractionator 90 imparting a part of its heat to the said body of oil.

The oil, now somewhat reduced in temperature, emerging through the heat insulated pipe 21 from the coil 20 may be returned to the heating zone, a bypass line 22 being provided for this purpose with a valve 23 which will then be open while valves 24 and 25 will be closed. Preferably, however, the oil leaving coil 20 is conducted through the closed coil 30 in contact with a body of oil maintained in the bottom of the fractionator 97, imparting a part of its heat to the said body of oil. When operating in this way the valve 23 will be closed and valves 24 and 25 open.

The oil, somewhat further reduced in temperature but still quite hot, is returned through the heat insulated pipe 35 to the heating coil 16 and the temperature of the oil is rapidly raised to the cracking point in transit therethrough. It is then passed through the heat insulated pipe 17 and is delivered to the stills 50 and 51 through the pipe connections 40 and 41. I may wish to extend the pipe 41 in future operation to effect a hot oil entry into the stills 52 and 53 also.

A series connection near the top between stills 50, 51, 52 and 53 is effected by means of the pipes 54, 55, 56, 57, 58 and 59. The said connections permit the free flow of fluids, both liquids and vapors, from the stills 50 and 51, to 52 and 53.

Within the stills 50, 51, 52 and 53 as the decomposition of the oil undergoing conversion progresses and the rearrangement of the molecules takes place, all that heavy component hereinbefore described as residue or fuel oil settles out and may be withdrawn by means of the pipe 78 connecting with the stills by means of branch pipes and valves 70, 71, 72, 73, 74, 75, 76 and 77.

A vapor line 60 is provided for conducting all vaporous components of the converted product from the cracking zone. It is to be

remembered that the evolved vaporous components have been hereinbefore described as an evolved heavy gas oil, an evolved light gas oil, evolved gasoline and gas.

- 5 The vaporous components entering the fractionator 90 through the pipe 60, preferably under super-atmospheric pressure, may be subjected to a reduction of pressure before entering the fractionator 90 and accordingly
 10 the pressure regulating valve 61 is provided in the vapor line 60. It is preferable, however, to provide a fractionator suitable to withstand the maximum operating pressure of the system for I contemplate practicing
 15 my invention, at different times, depending upon various factors, either by reducing the pressure in the fractionators or by maintaining a substantially equal pressure in the system, that is in the heating coil, stills, fractionating zone, and condensing zone.

Upon entering the fractionator 90 the said vaporous products are subjected to fractionation or rectification, the heavier components beginning to condense and precipitate to the
 25 bottom of the fractionator and the lighter components working their way up toward the top of the fractionator.

Where in the practice of my invention the coil 20 is provided submerged in the body of
 30 condensate in the bottom of fractionator 90 and where the highly heated oil from the heating coil 10 is passed therethrough the lighter vapors which might have been condensed and precipitated or otherwise mechanically held
 35 in solution are kept boiled off, and in consequence there may be regularly withdrawn, by means of the pipe 91 controlled by the valve 92, a heavy gas oil, such for example as one having an initial boiling point of approximately 450° F. Preferably said evolved heavy gas oil is recycled to the system by forcing it into the heating coil 16 at a suitable intermediate point by means of the hot oil pump 93.

45 The coil 4 provided in the top of the fractionator 90 by virtue of the relatively cool fresh oil charge passing therethrough in regulated flow imparts a regular amount of cooling to the warmer vapors in the top of the
 50 fractionator 90 whereby all the components falling within certain boiling limits may be condensed or knocked back, for example all components such as may boil above approximately 450° F.

55 At the same time there may be withdrawn overhead in vaporous form from the fractionator 90 all of the lighter components which may boil off at a predetermined end point such for example as all those boiling off below approximately 450° F.

It is to be understood that the top of the fractionator 90, in the practice of my invention, is balanced with the bottom. In other words while withdrawing overhead said approximately 450° F. end point components

there may be withdrawn from the bottom of the fractionator a recycle gas oil relatively free of both the heavy residue or fuel oil, and those lighter components which are intended to be passed overhead including all of the components from the lightest gases to the components somewhat heavier than gasoline but lighter than the original charging stock and also lighter than the recycle gas oil.

70 As hereinbefore disclosed it has been found that there is evolved a heavy fraction of gas oil, when operating as described, that lends itself readily to cracking while at the same time there is also evolved a light fraction of gas oil that is relatively difficult to crack.

75 In general it is advisable to determine in advance the best operating conditions from the standpoint of ultimate gasoline yield obtainable and the development of the readily crackable heavy gas oil for recycling before attempting to convert a virgin gas oil whose characteristics are more or less unknown. Toward this end it is quite desirable to determine before a run when changing to a new type of charging stock, the best operating condition with reference to temperature, pressure, and time and to predetermine the characteristics of the recycle gas oil which may be advantageously evolved. Considerable advantage may be realized in regularly 80 making small scale test runs of the various stocks for this purpose.

85 The vapors from the fractionator 90 are conducted through the vapor line 95 into the fractionator 97, entering the latter at about 90 the midpoint. Herein the entering vapors are subjected to a fractionating action similar to that in the fractionator 90, in that the heavier components of the vapor are condensed and precipitated toward the bottom of said fractionator, forming a body of condensate therein. It may be desired, when deviating from operating the entire system at balanced pressure, to reduce the pressure in the fractionator 97 below that existent in the 95 fractionator 90, and for this purpose a pressure regulating valve 96 may be placed in the vapor line 95.

95 As I have previously disclosed herein the evolved light gas oil component of the total 100 evolved product from the cracking or converting treatment may not be suited for recycling for further treatment under the conditions found most favorable for the charging stock used. Sometimes the amount of the 105 light gas oil of this nature which is evolved may be relatively small and again it may be relatively large.

110 Depending primarily upon the nature of the charge, the amount of light gas oil that 115 is evolved according to the present invention is governed by two factors; first by the fact that the initial boiling point of the said light gas oil remains constant, it being substantially of the order of the end point of 120

the gasoline component evolved which may be approximately 400° F.; and second by the fact that the end point of the light gas oil is predetermined and remains constant, it being substantially of the order of the predetermined initial boiling point of the heavy evolved gas oil, such for example as approximately 450° F. Since the evolved light gas oil is generally not adapted to crack readily at the calculated operating conditions maintained for the original charge, it is preferable to remove it entirely from the system for its presence in any amount tends to hamper the speed and economy of cracking. It is to be understood however that it must not be regarded as a waste product since it may form a very desirable charging stock for a different method of treatment or may be cracked separately under more favorable conditions, such as under higher temperatures and pressures or in a vapor phase cracking process.

To aid in effecting close fractionation in the fractionator 97 there is provided the previously mentioned coil 30 submerged in the body of condensate collecting in the bottom of the fractionator, and by regulatively passing the hotter oil from coil 20 through the coil 30 such gasoline components as may have been improperly condensed or dissolved are kept boiled off. This serves to produce at the bottom of this fractionator a light gas oil fraction which for example may have an initial boiling point of approximately 400° F. and an end point of approximately 450° F. Preferably this will be regularly withdrawn from the system by means of a pipe 99 and valve 98.

The lighter vapors passing upwardly in the fractionator 97, encounter progressively lower temperatures and are subjected to a cooling in the top of the said fractionator by virtue of the coil 2, through which the cold oil charge is passed in entering the system. The light gas oil components, such for example as those boiling above approximately 400° F. are condensed or knocked back and the lighter components, namely gasoline and gas, which may have an end point of approximately 400° F., are withdrawn in vapor form.

The emerging vapors from the fractionator 97 are conducted through a pipe 100 and put through a condensing coil 101. Emerging from the condenser 101 the cooled products are passed through a pipe 102, provided with a pressure regulating valve 103, interposed between the condenser and a collecting tank 104.

From the collecting tank 104 the gasoline or naphtha is discharged through a pipe 107 regulated by a valve 108 and the free or dry gas is vented through a pipe 105 and a valve 106.

Although in the foregoing disclosure of my invention many specific details of con-

struction have been set forth it should be understood that many variations may be effected without departing materially from the spirit and scope of the invention as defined by the appended claim. 70

What I claim is:

An oil conversion process which comprises heating a high boiling oil in a coil to a conversion temperature and permitting cracking to produce vapors of lower boiling oils, passing the vapors to a fractionator to effect separation between a high boiling condensate having substantially the same characteristics as said high boiling oil and a vapor of lower boiling constituents, returning the condensate to said coil, passing said vapor to a second fractionator to effect further separation, eliminating from the system the condensate so formed, passing partially heated oil withdrawn from said heating coil 85 in heat exchange with the condensate in the bottoms of said fractionators to re-boil said condensates, returning said heated oil to the coil for further heating, and condensing the vapors leaving said second fractionator to 90 form a desired final distillate.

In witness whereof I have hereunto set my hand this 18th day of June, 1928.
